UNITED STATES PATENT OFFICE.

GEORGE W. HINTON, OF ST. JOSEPH, MISSOURI, ASSIGNOR OF ONE-THIRD TO EDWIN C. RENAUD AND ONE-THIRD TO ROBERT R. POTEET, BOTH OF ST. JOSEPH, MISSOURI.

GUN-POINTING AND AUTOMATIC GUN-DISCHARGING MECHANISM, COMBINED.

1,309,091.

Specification of Letters Patent.

Patented July 8, 1919.

Application filed May 24, 1917. Serial No. 170,612.

To all whom it may concern:

Be it known that I, GEORGE W. HINTON, a citizen of the United States, residing at St. Joseph, in the county of Buchanan and State of Missouri, have invented certain new and useful Improvements in Gun-Pointing and Automatic Gun-Discharging Mechanisms, Combined, of which the following is a specification, reference being had therein to the accompanying drawing.

My invention relates to improvements in gun pointing and discharging mechanisms, combined, the objects of which are, first; to provide a mechanism of this class, by the use of which an explosive missile can be downwardly projected from an aeroplane, in flight, onto any desired visible object, for destroying the latter, and be aimed and projected with a high degree of accuracy, second; to so construct and arrange the parts of a mechanism of this class, that the duties of the gun pointer shall be extremely simple, and reduced to the minimum in number, and be performed while the gun pointer is kept in a comfortable position; third; to provide means whereby both the missiles and the energy by which they are projected, can be conserved for accurate and economical use, and the gun pointer shall not be subjected to more danger than is experienced by an ordinary aviator, fourth; to so construct the mechanism, that it shall yield to all of the oscillations of an aeroplane in flight, thereby avoiding the exertion of undue strain upon the parts of the aeroplane.

I attain these objects by the mechanism illustrated in the accompanying drawings, in which:—

Figure 1 is a reduced side elevation of the mechanism and of a portion of a hydroaeroplane, certain parts being omitted. Fig. 2 is a top plan of the gun platform and of the parts mounted thereon, together with certain portions of an aeroplane frame. Fig. 3 is a transverse section in detail, of the stop and waste cock, showing the parts in position for permitting passage of air therethrough. Fig. 4 is a similar section of the parts seen in Fig. 3, showing the parts in position for stopping passage of air through said cock and for exhausting air from the gun ports and passages. Fig. 5 is a transverse section in detail, of the lower end portion of the telescope sight, looking down-

ward. Fig. 6 is a side elevation in detail, 55 of the sighting mechanism, embodying a vertical section of a portion of the gyroscope. Fig. 7 is a front view in detail of the sighting mechanism and the gun, certain parts of the gun and platform being 60 broken away. Fig. 8 is a vertical section in detail, of one of the pneumatic steering valves. Fig. 9 is a horizontal section in detail of the pneumatic steering mechanism. Fig. 10 is a vertical section of one of the 65 various other forms of guns that may be used. Fig. 11 is a vertical section in detail, of the notched wheel and its adjusting mechanism.

Referring to Figs. 1 and 2, the gun platform 1 is secured on the inner gimbal ring 2, which latter is mounted for lateral oscillation in the outer gimbal ring 3, which is mounted for longitudinal oscillation in foundation ring 4. Said foundation ring 70 75 is rigidly secured on the frame 5, of an ordinary hydroaeroplane 6, which latter may be of any type suitable for either marine or land service, and for brevity, will hereafter be termed an aeroplane. Springs 80 5' are secured to said frame with their free end portions extending beneath said gimbal rings, for limiting their oscillations. Said aeroplane is provided with the rudder 7, for its lateral guidance. Said rudder is 85 secured on the oscillatably mounted rudder post 7', which latter is provided with rudder arm 7''. The free end of said arm is engaged with piston rod 8, which has pistons 9 and 10 secured on its respective ends. Said 90 pistons are slidably mounted in cylinders 11 and 12, respectively, which cylinders are secured on the rear portion of aeroplane frame 5.

The free extremity of arm 7'', (see Fig. 95 9,) is provided with spring 8', which is adapted, normally, to hold said arm and the thereby controlled rudder 7, (see Fig. 1,) in alinement with aeroplane 6. Cylinders 11 and 12 are respectively connected with air 100 valve cylinders 13 and 14, (see Fig. 1,) by hose 11' and 12'. Said air valve cylinders are connected with valve chamber 15, through their valves 16, (see Fig. 8), but one of which is shown. Said valve is opened by 105 pressure upon the stem 19 of piston 17, which latter is adapted to be manually moved downward by pressure upon its knob

19, said knob being adapted to be raised by spring 19", which is mounted on the piston stem 19', which latter connects said knob and piston.

5 Valve 16 is actuated to close by the spring 18. Said valve cylinder is provided with an exhaust port 20.

Valve chamber 15 is connected by hose 21, with air tank 22, (see Fig. 2,) which latter 10 is supplied with air, pumped under pressure, through hose 23, by the air pump 24, which may be driven by a windmill 24', as seen in Fig. 1; or the same may be driven by a clutch connection with the obscured portion 15 of engine shaft 25; and since the structural details of said pump form no part of this invention, the same are neither shown nor described.

The foregoing described parts form pneumatic guiding means, whereby the aeroplane 20 6 is laterally guided, thereby guiding said aeroplane and the thereby carried gun 26, into proper position to be discharged. Said gun is rigidly secured on platform 1, and 25 is arranged to point downward. Referring to Fig. 7, the inwardly projecting rifles 26' are formed in the usual spirals on the inner surface of gun 26, which is provided with the removable breech block 26'. Said gun is 30 also provided with two diametrically opposite air inlet ports 27, but one of which is shown. Said ports are each provided with a valve 28, and since said valves are alike in construction and operation, but one is 35 described.

The free depending end of lever 28' is adapted to be held outward by a missile 29, while in said gun, for keeping said valve open, while air is flowing therewith into 40 gun 26.

Port 27 is of such form that said passage of air impinges upon said valve and closes the same after the upper end of missile 29, in being discharged, has passed the lower end 45 of lever 28'.

Said missile has the preferably soft metal ring 29', of lesser breadth of face, secured on its lower end portion, which ring is adapted, by the weight of said projectile, to 50 have rifle notches cut therein by the upper ends of rifles 26", when said ring is lowered thereon, in the placing of said projectile in gun 26. The upper end of missile 29 is similarly provided with the metal ring 29", 55 of greater breadth of face, which latter ring is of such degree of hardness, that it supports said missile, by resting upon the upper ends of rifles 26", and is of such consistency, that when the pressure of air, admitted into said gun, onto the upper end of 60 said missile, forces the latter downward, it carries said ring past the upper ends of rifles 26", thereby cutting rifle notches in said ring, which releases said projectile, 65 which is thereafter discharged from said

gun, by said pressure of air, upon which the valves 28 are closed, as described, and normally remain in this position.

Referring to Figs. 6 and 7, the telescope sight 30 is provided with focusing wheel 70 30'. Said sight is pivotally mounted for lateral oscillation in ring 31, which ring is pivotally mounted for fore and aft oscillation in the sight mountings 32, which latter are secured on gun platform 1. Said sight 75 is provided with the usual vertical line 33 and the horizontal line 34, (see Fig. 5,) formed and placed in said telescope sight in the usual manner, well known to the optician's art.

Referring to Figs. 6 and 7, a standard 35 is formed with each side of the front portion of ring 31, and projects thereabove. The ends of the segmental gear rack 36 are secured on the upper ends of said standards. 85 Said rack has the coarser wind gage dial 37, formed on its exposed side. Pointer 37' is secured on the barrel of sight 30, and points to the various markings of said coarser dial, in its various adjustments.

Worm 38 has its stem portion rotatably mounted in the worm carrier 39, which is oscillatably mounted on said barrel. The rear end portion of said carrier is actuated to move upward by spring 39', for moving worm 38 downward and yieldably holding the same in close engagement with rack 36.

The thus yieldably held worm carrier and the thereby carried worm may be manually 100 lifted, for disengaging said worm from said rack and permitting direct manually actuated movement of said sight, either right or left, for quick adjustment of said sight. The right end of the stem portion of said worm has hand wheel 40 secured thereon. The face of said wheel has the finer dial 40' formed thereon, the markings of which indicate the fractional parts of one revolution of said wheel.

The described parts will hereinafter be termed the wind gage.

Referring to Figs. 6 and 7, the pinion shaft 41 is slidably and rotatably mounted in the upper extremities of telescope sight 115 mountings 32, and has gear pinion 42 secured thereon. Said shaft has thrust collar 43 secured on the right end thereof and hand wheel 44 secured on its opposite end. The upper end of the designated mounting 32 120 terminates in a bracket 32', which extends over said pinion and downward, its extremity loosely encircling shaft 41, forming an abutment for one end of spring 45, which spring encircles shaft 41.

The opposite end of said spring presses against collar 43, for moving the same and the therewith connected parts toward the right, as hereinafter described.

Pinion 42 at all times engages gear seg-

ment 46, which is formed on the upper end of the designated one of standards 35.

The described parts will be termed the sight oscillating mechanism.

5 Oscillating segment 46, has oscillation degree lines 46' formed thereon. Degree segment 47 is adjustably secured on segment 46, by set-screw 47', seen in Fig. 6.

Shoulder 41" is formed on shaft 41; and is 10 adapted to be engaged by said degree segment for holding said shaft and the therewith connected parts toward the right, from the position shown in Fig. 7.

Referring to Figs. 7 and 11, index wheel 15 48 is formed on shaft 41 and has index lines 48' on its face. Stud 48" is formed with said index wheel. Said stud is adapted to enter any one of the adjusting holes 49", which are formed through the notched wheel 20 49, for holding said notched wheel in variously adjusted rotative relation, to said index wheel.

Notched wheel 49 is slidably and rotatably mounted on shaft 41 and is yieldably held 25 against index wheel 48, by spring 49", for yieldably holding said wheels in their described engagement.

Notched wheel 49 has notch 49' formed in its periphery. Dog 50 is formed on the upper extremity of trigger 51, which is L shaped, and is pivotally mounted on the designated one of sight mountings 32. The lower end of said trigger is adapted to hold the free end of cock stem arm 52, against 30 movement toward the left. The lower end of said arm is secured on the right end of cock stem 53, which is oscillatably mounted in said sight mounting 32. The other end portion of said cock stem is similarly 35 mounted in cock body 54.

Referring to Figs. 3 and 4, said cock stem has air port 53' formed therethrough, and waste port 53" formed therein, extending at a right angle from said air port through one 45 side of said stem. Cock body 54 has port 54' formed horizontally through both sides thereof, and waste port 54" formed vertically through its upper side. The described cock is commonly called a stop and waste 50 cock, and is adapted to have its stem rotated from the position seen in Fig. 4 to the position seen in Fig. 3. The right side of said cock body is connected with tank 22, by hose 55, (see also Fig. 2,) while the left side of 55 said cock body is connected with the bifurcated gun passage 56, the bifurcations of which extend therefrom into ports 27, seen in Fig. 7. Cock actuating spring 52', as seen in Figs. 6 and 7, is mounted on cock stem 53 60 and has one of its ends connected with arm 52, while its other end rests upon gun platform 1. Said spring is adapted to move the free end of said arm toward the left from the lower end of trigger 51, to the position

shown, for opening communication between 65 tank 22 and the upper end of gun 26. The latch bolt 52" is slidably mounted in supports 32.

The left end of said bolt is adapted to be slid into the path of travel of arm 52, for 70 holding the same against the action of spring 52'.

The previously described parts form automatically operated gun discharging means.

Referring to Figs. 1 and 6, gun platform 1 75 has shaft support 57 connected therewith and depending therefrom. The lower end of fly wheel shaft 58 is rotatably mounted in said support, while its upper end is similarly supported in the central part of the 80 upper portion of gun platform 1. The upper fly-wheel 59 is secured on the upper end portion of said shaft. Said upper fly-wheel has the upper bevel gear 59', formed on its under surface. Sleeve 60 is rotatably 85 mounted on shaft 58, and has fly-wheel 61 secured on its upper end portion. The last mentioned wheel has bevel gear 61' formed on its upper surface. Said fly-wheels are oppositely rotated by the hereinafter described 90 electric motor. The rotations of said fly-wheels are synchronized by the idle gear pinion 62, which is rotatably mounted on pinion shaft 62', the ends of which shaft are securely mounted in gun platform 1, but one 95 end of which is shown in Fig. 6. Said shaft has opening 62" formed through the central portion thereof, through which the upper end portion of shaft 58 extends.

Said pinion shaft is thus formed to give 100 the same rigidity and allow both ends of said shaft to be supported.

Field 63 of the electric motor is secured on the lower end portion of sleeve 60. Said field is provided with the two collector rings 105 64 and 64'. Said rings are connected with the unshown windings of said field, and are respectively provided with brushes 65 and 65', which are connected with dynamo 66, (see Fig. 1,) by lead wires 67 and 67'. 110 Armature 68 is secured on the lower end portion of shaft 58, and is provided with segmental commutator 69, which latter is provided with brushes 70 and 70', which are respectively connected with lead wires 67 115 and 67', by brush wires 71 and 71', said connections being not shown.

It will be understood from the foregoing, that the described electric motor is shunt connected with dynamo 66, and that said field and armature are mounted for rotation in opposite directions. Said motor is thus constructed and operated for the purpose of opposing and counteracting all precessional force that may be exerted by the field and armature; thus providing a motor that will 120 act as a gyroscope.

The oppositely rotated fly-wheels 59 and

61, form the prime elements of the gyroscope, in which said fly-wheels counteract each other's precessional force.

Since the structural details of the electric 5 motor form no part of this invention, further than have been described, said details are neither shown nor described.

It will be seen in Figs. 1 and 6, that said 10 motor and shaft support 57, act as a pendulum, depending from the therewith connected gun platform 1, and it will be understood that said pendulum, by the gravity thereof, would return said platform to level 15 position, should the same become tilted from any cause.

It will be further understood, that the 20 gyroscopic force of fly-wheels 59 and 61, which are rotated at a high speed, would so rigidly maintain said gun platform in its 25 level position, that great force would be required to perceptibly tilt the same. I thus provide a stabilized gun platform, upon which gun 26 is practically, at all times held in a true vertical position, with its muzzle 30 end pointing downward.

In operation with the parts in the position seen in Figs. 1 and 6, the gun pointer 72 and pilot 74 keep a sharp look-out for a target, such as a submarine boat, a 35 warehouse, or other object. This lookout is maintained, with the assistance of the usually used field glasses, not shown.

Said gun pointer determines his height 40 from the earth's surface, by looking at the barometer 73. It will be understood said gun pointer is also provided with the usual instruments, such as a speedometer, compass, and the like. Said gun pointer consults said instruments in the making of the regular 45 gun pointer's calculations, by which he sets the previously described wind gage, and the automatic gun discharging mechanism.

Pilot 74 is provided with sighting rods 75 and 75', secured vertically on the upper surface 45 of the front end portion of the aeroplane 6.

When either the pilot or the gun pointer sees a desirable target, he informs the other party. Said pilot heads said aeroplane directly 50 toward a point in the air, above said target, approximately guiding the aeroplane by keeping said sighting rods in alinement with said target.

At this juncture, with the valves 28 in 55 their previously described normal position, gun pointer 72 with one hand moves the free end of cock lever 52, (see Fig. 6,) toward the right, and locks the same in cocked position, by sliding the left end of latch bolt 52" 60 in front of it, thereby latching cock stem 53 in closed position, as seen in Fig. 4. He then removes the breech block 26', from over the breech of gun 26; then takes a projectile 29 from an unshown adjacent magazine, 65 and places the same in said gun, in the po-

sition indicated in Fig. 7, and thereafter primes said projectile with the usual fulminate primer, not shown. He then replaces breech block 26'.

Said gun pointer then makes the previously 70 mentioned calculations, and sets his wind gage and automatic gun discharging mechanism, in accordance therewith.

Said gun pointer then grasps hand wheel 44, and thereby slides shaft 41 toward the 75 left, overcoming spring 45, (see Fig. 7), until shoulder 41" is past the adjacent end of degree segment 47, after which he rotates said hand wheel counter-clockwise. Said gun pointer then liberates said hand wheel, 80 upon which said shoulder is moved against the outer surface of said degree segment, by spring 45. This holds said shaft and the thereon formed index wheel 48 toward the left, from the position shown, with the 85 continuous periphery of said index wheel in register with the end portion of dog 50, for preventing said dog from entering notch 49'.

Said gun pointer then moves latch bolt 90 52" toward the right, thereby releasing the free end of lever 51, which moves dog 50 against said index wheel.

Further counter-clockwise rotation of hand wheel 44, oscillates telescope sight 30, 95 thereby enabling said gun pointer to therethrough see the surface of the earth, at a point, far in advance of aeroplane 6.

Pilot 74 releases his hand operated mechanism, (not shown,) when the target 100 76 (see Fig. 5,) comes into view through the sight 30, said mechanism being the usual lateral steering devices now used on aeroplanes. The gun pointer 72, now laterally steers the aeroplane 6 by manually operating the previously described pneumatic steering mechanism, with his right hand. He thus directs said aeroplane in such manner that the vertical line 33 is kept in alinement with the center of target 110 76, while with the other hand, he rotates hand wheel 44, clockwise; thereby bringing and thereafter keeping horizontal line 34, also in alinement with the center of target 76, as seen in Fig. 5.

Said gun pointer maintains said alinement until degree segment 47 is carried past shoulder 41", upon which spring 45 moves shaft 41, and the thereon carried hand wheel 44, from their described position, to 115 the right, to the position shown.

This lateral movement of said parts, notifies said gun pointer, that the gun discharging point has been closely approached. He thereupon redoubles his care in maintaining said alinement of his sight with the center of target 76. The previously described lateral movement of the shaft 41, carries index wheel from the end of dog 50, which dog is thus liberated for entry into 120 125 130 135 140 145 150 155 160 165 170 175 180

notch 49'. Continued clockwise rotation of hand wheel 44, rotates notched wheel 49, until notch 49' is thereby moved into register with the end portion of dog 50. At this 5 juncture spring 51' oscillates trigger 51, moving said dog into said notch. This movement moves the lower end of said trigger from engagement with the free end of cock stem arm 52, which, by the action of 10 spring 52', is moved from the lower end of said trigger to the position shown in Fig. 6. This movement of said arm, rotates cock stem 53, from the position seen in Fig. 4, to the position seen in Fig. 3, thereby admitting air under pressure from tank 22, through hose 55, cock 54, gun passages 56, and ports 27, into gun 26.

Said pressure of air moves projectile 29, downward, discharging the same from said 20 gun, onto target 76.

After said projectile passes the lower ends of levers 28', the inertia of said levers and valves 28, retard their inward movement, which movement is caused by impingement 25 of air in passing said valves, which ultimately closes the same. This retardation is such, that said valves are not fully closed until immediately after said projectile has left gun 26. This action of said valves insures active pressure upon missile 29 30 throughout its travel in said gun, and also conserves the air in tank 22.

While I have shown and described the gun in the foregoing manner, and air inlets 35 for discharging a missile therefrom by pressure of air, it is evident that the gun 26 and its discharging mechanism, could be so modified as to adapt the same for using a charge of explosive matter for propelling 40 the projectile, instead of using air, without departing from the spirit of my invention, which I reserve the right to do.

One of the variously modified forms in which said gun and its discharging mechanism could be made, is illustrated in Fig. 45 10, in which the oscillatably mounted trigger 51, (see Fig. 6,) normally holds arm 77, (see Fig. 10,) against the action of spring 79. Said arm is secured on the oscillatably 50 mounted shaft 78, and has gun hammer 80 formed therewith. The free end portion of said hammer is adapted to strike the firing pin 81, which is slidably mounted in breech block 82 of the recoil gun 83. Since guns 55 of the recoil type are well known, and since the structural details of said recoil gun form no part of this invention they are neither fully shown nor described.

Having fully described my invention, 60 what I claim as new and desire to secure by Letters Patent, is:—

1. The combination with the frame of an aeroplane of a gyroscopically stabilized gun platform supported by said frame; aeroplane guiding means mounted on said plat-

form whereby said aeroplane is guided; a gun mounted on said platform said gun being adapted to have a missile downwardly discharged therefrom; gun sighting means oscillatably mounted on said platform for 70 sighting said gun; spring actuated gun discharging means for discharging said gun; discharge holding means whereby said gun discharging means is held against the action of said spring; and automatic releasing 75 means operated by said sighting means for releasing said holding means when said sighting means has been oscillated to a predetermined point.

2. The combination with an aeroplane 80 frame of a gyroscopically stabilized gun platform supported by said frame; a gun mounted on said platform for projecting a missile against a target; sighting means mounted on said platform for laterally 85 sighting said gun; and guiding means controlled from said platform whereby said aeroplane is laterally guided for bringing and holding said sighting means in alignment with said target.

3. The combination with the frame of an aeroplane of a gyroscopically stabilized gun platform supported by said frame; a gun mounted on said platform for downwardly projecting a missile against a target therebelow; sighting means for sighting said gun said sighting means being mounted on said platform for both lateral and longitudinal oscillation; a manually operated wind gage whereby said sighting means is laterally oscillated to compensate for the lateral action of wind on said missile while it is in flight; power operated guiding means whereby said aeroplane is laterally guided for lateral alinement of said sighting means 95 with said target; manually operated controlling means whereby said lateral guiding means is controlled from said platform; manually operated oscillating means whereby said sighting means is longitudinally oscillated for longitudinal alinement of said sighting means with said target; spring actuated gun discharging means for discharging said gun; holding means whereby said discharging means is held against the 100 action of its said spring; and releasing means whereby said holding means is automatically released when said sighting means has been longitudinally oscillated to a predetermined point.

4. In a gun pointing and gun discharging mechanism, combined, the combination with a portably mounted gun and means for moving said mountings and the thereon carried gun; of gun sighting means mounted with 105 said gun, said sighting means being mounted for oscillation through a vertical plane; manually operated oscillating means whereby said sighting means is oscillated; limiting means whereby said oscillation is limit- 110

- ed; limit setting means whereby said limiting means is set for limiting said oscillation at a predetermined point; spring actuated gun discharging means; holding means whereby said actuating means is held against the action of its spring; and releasing means whereby said holding means is released when said oscillating means reaches the set limit of its oscillation.
5. The combination with the frame of an aeroplane of a gun platform oscillatably mounted thereon for free oscillation both laterally and longitudinally, of a gyroscopic fly-wheel for stabilizing said platform in a horizontal position by rotation of said fly-wheel through a horizontal plane; electrically energized rotating means whereby said fly-wheel is rotated; electric energy generating means supported by said aeroplane frame for energizing said rotating means; power driven rotating means whereby said generating means is driven; and a pendulum for yieldably holding said platform in its horizontal position.
10. 5. The combination with a gun platform mounted on an object for both lateral and longitudinal oscillation; of a gyroscopic fly-wheel adapted to stabilize said platform in a horizontal position by rotation of said fly-wheel through a horizontal plane; a shaft for said fly-wheel; shaft mounting means connected with said platform in which said shaft is rotatably mounted, said shaft being extended from said platform to a point considerably therebelow; and an electric motor connected with the lower end portion of said shaft for rotating the latter, the gravity of said motor, shaft, and mounting means being such that they together are adapted to act as a pendulum for yieldably holding said platform in a level position.
15. 6. The combination with a gun platform and an aeroplane, of mounting means whereby said platform is so mounted in a level position on said aeroplane as to permit free lateral and longitudinal oscillation of said aeroplane without moving said platform from its level position; yieldable holding means whereby said platform is yieldably held in its horizontal position; a gun mounted on said platform for downwardly projecting a missile on a target therebelow; sighting means supported by said platform through which said target is sighted; and aeroplane guiding means whereby said aeroplane is guided for laterally bringing and holding said sighting means in alignment with said target.
20. 8. The combination with a gun platform provided with a gun mounted thereon in a downwardly pointed position; of platform mounting means on which said platform is mounted for free longitudinal and lateral oscillation; a carrier such as an aeroplane and the like on which said platform mounting means is carried; a pair of gyroscopic fly-wheels supported by said platform the axis of one of said fly-wheels passing through the axis of the other one of said fly-wheels; rotating means whereby said fly-wheels are rotated in opposite directions for stabilizing said platform and the thereon mounted gun; synchronizing means whereby the rotations of said fly-wheels are synchronized; and yieldable holding means whereby said platform and the thereon mounted gun are yieldably held in their respective positions.
25. 9. In combination with a set of gimbal rings adapted to be mounted on an aeroplane; a platform adapted to have a gun and gun sighting means mounted thereon said platform being mounted on the inner one of said set of gimbal rings; shaft mounting means connected with said platform and depending therefrom; a shaft having its upper end rotatably mounted in said platform and its lower end similarly mounted in said shaft mounting means; a gyroscopic fly-wheel secured on the upper end portion of said shaft; a sleeve rotatably mounted on said shaft; another gyroscopic fly-wheel secured on the upper end portion of said sleeve; a field of an electric motor secured on the lower end portion of said sleeve; an armature of said electric motor secured on the lower end portion of said shaft adjacent to said field; electric energizing means whereby said field and armature are energized; and synchronizing means whereby the rotations of said fly-wheels and the therewith connected field and armature are synchronized.
30. 7. The combination with a gun platform and an aeroplane, of mounting means whereby said platform is so mounted in a level position on said aeroplane as to permit free lateral and longitudinal oscillation of said aeroplane without moving said platform from its level position; yieldable holding means whereby said platform is yieldably held in its horizontal position; a gun mounted on said platform for downwardly projecting a missile on a target therebelow; sighting means supported by said platform through which said target is sighted; and aeroplane

Witnesses:

ROBERT R. POTEET,
EDWIN C. RENAUD.

In testimony whereof I affix my signature in the presence of two witnesses.

GEORGE W. HINTON.
